(57) CLAIM

The ornamental design for an applicator for a semi-permanent tattoo as shown and described.

DESCRIPTION

FIG. 1 is a top, perspective view of an ornamental design for an applicator for a semi-permanent tattoo according to the present invention;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a back view thereof.

The broken lines shown are for the purpose of illustrating portions of the applicator for a semi-permanent tattoo that form no part of the claimed design.
